(57) **CLAIM**

The ornamental design for a syringe lock, as shown and described.

DESCRIPTION

FIG. 1 is a perspective view from the bottom of an embodiment of a syringe lock of the present disclosure;

FIG. 2 is a perspective view from the top of the device of FIG. 1;

FIG. 3 is a bottom view of the device of FIG. 1;

FIG. 4 is a top view of the device of FIG. 1;

FIG. 5 is a front elevational view of the device of FIG. 1;

FIG. 6 is a back elevational view of the device of FIG. 1;

FIG. 7 is a left elevational view of the device of FIG. 1; and,

FIG. 8 is a right elevational view of the device of FIG. 1. Broken lines are used to illustrate portions of the syringe lock, other broken lines illustrate environmental subject matter, neither form no part of the claimed design.
